UNITED STATES PATENT OFFICE.

WILLIS F. HOOD, OF DEERFIELD, MICHIGAN.

ADJUSTABLE BARREL-COVER.

SPECIFICATION forming part of Letters Patent No. 249,939, dated November 22, 1881.

Application filed February 21, 1881. (Model.)

To all whom it may concern:

Be it known that I, WILLIS F. HOOD, of Deerfield, county of Lenawee, and State of Michigan, have invented a new and useful Improvement in Adjustable Barrel-Covers; and I declare the following to be a full, clear, and exact description of the same, such as will enable others skilled in the art to which it pertains to make and use it, reference being had to the accompanying drawings, which form a part of this specification.

The object of my invention is to provide a barrel-cover which may be fitted to barrels of various sizes; and it consists in the combination, with a stationary cover-section, of a flexible band secured thereto and adjustable to fit barrels of various sizes, and a movable section pivoted centrally to said stationary section, and adapted to close and open a portion of the top of the barrel, as will be hereinafter more particularly described.

In the accompanying drawings, Figure 1 is a perspective view of my improved barrel-cover with the movable section partly swung open. Fig. 2 is a bottom view of the cover with the movable section closed. Fig. 3 is a view in elevation of the top portion of a barrel with the cover attached.

The letter B designates the stationary cover-section, which is about semicircular in shape, and preferably made of sheet metal. To the under side of this section, near the middle of its curved edge, is secured edgewise the flexible band C, which is also preferably made of sheet metal. This band is intended to embrace the upper margin of a barrel, as shown in Fig. 3. At one of its ends, and near its other end, the band C is provided with outwardly-projecting ears C'C', through both of which passes a bolt, C², provided with a nut, in the usual manner, in order that the ears may be drawn together or allowed to separate, to enable the band to embrace a barrel of greater or less size,

as required. I prefer to have one end portion of the band projecting beyond the ear, as shown at C³, Figs. 1 and 2, in order that the projecting portion may serve as a bearing upon which the other end may slide in tightening the band; but this projecting portion may be omitted without departing from my invention.

The letter D designates a centrally-pivoted cover-section, secured to the stationary section by a pivot, D', and adapted to turn about this pivot, so as to open and close about one-half of the top of the barrel. The section D is of a size a little larger than the largest space which the band can embrace beyond the stationary section, and may be provided with a knob by which it may be turned, as at e, and a stop, as at f, for limiting its movement.

I am aware that a barrel-cover has been composed of a stationary section attached to a band, and a door-section pivoted to said stationary section, and I do not claim such construction, broadly.

What I claim is—

1. An adjustable barrel-cover composed of a stationary segmental section attached to an adjustable flexible band adapted to embrace the exterior of the top of a barrel, and a movable section pivoted to said stationary section, and adapted to swing over it, substantially as described.

2. The combination, with the stationary and movable cover-sections, of the flexible band secured to the former and provided with the ears, and the end portion projecting beyond one of said ears, and a bolt passing through said ears, substantially as described.

In testimony whereof I sign this specification in the presence of two witnesses.

WILLIS F. HOOD.
